UNITED STATES PATENT OFFICE.

RALPH M. JACKSON, OF LA HABRA, CALIFORNIA.

FUMIGATING APPLICATOR.

Application filed September 29, 1924. Serial No. 740,568.

To all whom it may concern:

Be it known that I, RALPH M. JACKSON, a citizen of the United States, residing at La Habra, in the county of Orange and State of California, have invented a new and useful Fumigating Applicator, of which the following is a specification.

My invention relates to measuring devices and gasifiers for applying liquid gases for 10 fumigating purposes under covered trees.

Among the objects of this invention is to provide efficient means in a device of this character whereby vertically disposed lever actuating means for producing pressure may 15 be employed with a vertically disposed pump measuring means, and manually operated nozzle check valve means co-operating with said pump means, and means whereby a series of fixed measurements may be measured and discharged in intermittent expulsions from said pump means through discharge nozzle means being laterally spaced from and in approximate horizontal alignment with the lower end of said pump means 20 and at an appreciable distance from said pump means.

Other objects may hereinafter appear.

The accompanying drawings clearly illustrate the structure.

Fig. 1, of the drawings is a side elevation of my device with portions of the structure cut away for clearness including a portion of the supply receptacle and shows in section the pump mechanism associated therewith.

Fig. 2, is a perspective back end view of the device.

Fig. 3, is a detail plan view of the measure controlling member, detached.

Fig. 4, is an enlarged fragmentary portion of the pump cylinder and shows therein a sectional detail of the pump piston and pump valve mechanism.

The invention includes a supply receptacle for fumigating fluid, vertically disposed pump measuring and discharging means for measuring and discharging fluid from said receptacle and vertically disposed lever actuating means for said pump means, atomizing nozzle means and manually controlled check valve means associated with said nozzle means.

The device is illustrated in the present preferred construction but it is to be understood that various mechanical alterations within the skill of the workmen may be

made without departing from the scope of the invention as claimed.

The structure shown comprises a supply receptacle 1, for fumigating material. A 60 pump cylinder 2 connected at its upper open end to the bottom of receptacle 1 and at its lower end to a base 3. A pump piston 4 working in the cylinder 2 is stopped by the shoulder 4^a. A piston rod 5 actuating the 65 piston 4 and valve 6 extends upwardly from said piston and through a vent dome 7 and packing gland 8 provided at the top of receptacle 1 and connects at its upper end to a yoke 9. Connecting rods A, A attached 70 to the outer ends of yoke 9 extend downwardly and connect to cranks B, B the same being attached to shaft 10 having a pivotal bearing 11 the same being attached to base 3. Lever 12, which is secured to shaft 10 75 at its lower end projects upwardly and through a measure controlling member 13 and at its upper end has an operating handle 14. Supporting member 15 at its upper end forms a support for one end of member 80 13 and projects downwardly around one side of receptacle 1 to base 3 and is secured thereto. Supporting member 16 which is secured at its lower end to base 3 projects 85 upwardly and around one side of receptacle 1 and at its upper end supports one end of a handle 17 for carrying the device. Supports 15 and 16 are clamped to receptacle 1 by tie rods C, C. Fluid discharge line 18 having the valve 19 is connected at one end 90 to the lower end of pump cylinder 2 and projects laterally therefrom and at its other end connects with atomizing nozzle means 20. A manually controlled check valve 21 provided at the nozzle to control the free 95 flow of fluid through the nozzle and to aid the pump action is connected to an actuating extension 22 which extends through a packing gland 23 to a connecting member 24 which is pivotally connected to crank 25, 100 said actuating extension extending through said member 24 and slidably fitted therein is provided with a compensating spring 26 and adjustment 27. Adjusting screws 28 and 29 are provided for the measure controlling member 13. Vent line 30 connected at its upper end to vent dome 7 projects downwardly to a point in substantial horizontal alignment with discharge line 18 and thence laterally to a point adjacent the nozzle means 20. A glass tube 31 is provided 105 for determining the quantity of fluid in

105

110

supply receptacle 1. A filler port 32 having the cap 33 is provided in the dome 7. In a device of this character it is essential to build a structure of extreme lightness consistent with durability and in order to obtain such structure aluminum is extensively used even in the receptacle and as it is at present deemed most practicable to weld the seams therein it is important, due to the expense of said welding to limit the structure to as few welds as possible, hence the packing gland casting I prefer to construct to include the vent dome and filler port. With this structure one weld serves for three purposes, namely; vent dome, packing gland and filler port.

Due to the corrosive character of the fumigant of common use I prefer to use special packing means in the pump piston, this packing comprises an expanding metal ring 34 and two expanding metal rings D, D on either side of an asbestos fabric packing 35, all within a groove 36 as shown in Fig. 4. With such corrosive fumigant the pump cylinder and piston rings are apt to score or become roughened, hence the said fabric packing, preferably asbestos, is employed to insure a perfect piston seal, and the rings D, D function to prevent particles of said packing from working out past the piston and into the said atomizing nozzle and clogging the same. Individual ring grooves may be provided for the rings D, D if desired.

In operating the device the measurement of fluid is accomplished with a uniform stroke of the lever 12 controlled by the member 13 a full stroke accomplishing the measurement of five units, the measurement of one unit being accomplished by springing the lever 12 to the right so it will engage with the screw 29. For example, if a measurement of eleven units were desired the operator would draw the lever 12 backward until it engaged with the screw 28, the movement would be transmitted by the cranks B, B and the connecting rods A, A to piston rod 5 and would raise the valve 6 slightly, through lost motion in the valve mechanism but sufficient to permit the space in the pump cylinder below the piston to fill, the operator then would throw the lever forward causing the valve to close and a continuation of such forward movement until the piston engaged with the shoulder 4^a would cause the expulsion from the pump of five units of fluid, a repetition of such operation would accomplish the measurement of ten units and it would then require the employment of the means provided for the measurement of one unit to accomplish the measurement of eleven units. Other measurements of different denominations would be accomplished in the same manner using the one unit measure when the five units could

not be employed. By means of the lever 12 the fluid is forced from the pump through the nozzle with sufficient pressure to convert the fluid into vapor. The valve 21 by checking the free flow of fluid through the line 18 and nozzle 20 provides means whereby a series of fixed measurements may be measured and discharged in intermittent expulsions from the pump means through the nozzle means. The nozzle check valve 21 is connected with the pump actuating means by the extension 22 and connection 24 and closes simultaneously with the full forward stroke of the lever 12 but remains closed during the backward stroke of lever 12; during the backward stroke the member 24 slides on the valve actuating extension 22 and continues to slide until lever 12 has completed the backward stroke and a forward stroke when the member 24 engages with spring 26 closing the valve 21, the valve having been opened by liquid pressure from the pump through line 18 and port 37, on the forward stroke of the lever. Adjusting means 27 is provided on the extension 22 back of spring 26 for accurate timing of valve 21. Since the piston 4 stops on the shoulder 4^a simultaneously with the closing of valve 21 I prefer to employ the compensating spring 26.

In my patent of Feb. 20, 1923, No. 1,446,093 I show vertical lever means in a device of this character with a horizontal pump cylinder and in my patent of Dec. 11, 1923, No. 1,477,125 I show horizontal lever means with a vertical pump cylinder and in the device described herein I have combined the advantages of a vertical lever with the advantages of a vertical cylinder and have also adapted my device to the use of a positive acting manually operated nozzle check valve.

Having thus described my invention I claim:

1. A portable fumigating applicator adapted to be carried by hand, including a supply receptacle for fumigating fluid, base means, supporting means attached to said base means, vertically disposed pump measuring and discharging means for measuring and discharging said fluid from said receptacle the measurement thereof representing a plurality of units, vertically disposed lever means for actuating said pump means said lever being supported by said supporting means, a measure controlling member for controlling the said lever means and for determining the unit measurement of the said measuring means, atomizing nozzle means laterally spaced from the said pump means, and fluid conducting means for connecting said nozzle means with said pump means, and a positive acting manually operated valve means associated with said nozzle means and co-operating with said lever and pump means, said valve adapted to control

the free flow of fluid through the said nozzle means.

2. A portable fumigating applicator adapted to be carried by hand, including a supply receptacle for fumigating fluid, pump measuring and discharging means for measuring and discharging said fluid from said receptacle the measurement thereof representing a plurality of units, lever means for actuating said pump means and a measure controlling member for controlling the said lever means and for determining the unit measurement of the said measuring means, atomizing nozzle means laterally

spaced from the said pump means, and fluid 15 conducting means for connecting said nozzle means with said pump means, and a positive acting manually operated valve means associated with said nozzle means and co-operating with said lever and pump means, 20 said valve means adapted to control the free flow of fluid through the said nozzle means.

In testimony whereof I hereunto affix my signature in the presence of two witnesses.

RALPH M. JACKSON.
